FIG. 1

FIG. 2

FIG. 3

FIG. 4

FIG. 5

FIGURE 1 is a left side, top and front perspective view of an electronic musical instrument of the keyboard type, showing my new design;

FIGURE 2 is a top plan view;

FIGURE 3 is a side elevational view, the opposite side being substantially a mirror image thereof;

FIGURE 4 is a rear elevational view; and

FIGURE 5 is a bottom plan view thereof.

The conventional keyboard is fragmentarily shown by means of solid lines and is continuous across the instrument as indicated by the dot-dash lines.

I claim:

The ornamental design for an electronic musical instrument of the keyboard type, substantially as shown and described.
